MACHINE FOR APPLYING STAMPS
AND LABELS

James A. Sanders, Lando, S. C.

Application January 18, 1935, Serial No. 2,417

1 Claim. (Cl. 216—33)

This invention relates to a machine for affixing stamps to packages, and more especially to the affixing of sales tax stamps to packages of cigarettes which are required by the laws of many 5 States to be affixed thereto by the dealer or wholesaler before the cigarettes are sold for consumption. Heretofore, this operation has been carried out by hand, which in the case of large 10 retailers and wholesalers has necessitated the employment of operators for this purpose, requiring a great amount of expense.

It is an object of the invention to provide an apparatus into which packages of cigarettes can be fed automatically for the affixing of tax stamps 15 thereon.

It is another object of the invention to provide an apparatus for affixing stamps to packages of cigarettes which will accommodate various sizes of packages by means of simple and 20 quickly made adjustments.

It is a further object of this invention to provide means for applying labels, stamps and the like to packages and having means for receiving a quantity of the packages and automatically 25 conveying the packages, one following the other, through the apparatus, and also having means for affixing stamps, labels and the like to the packages while they are being conveyed, in constant movement, through the machine.

Some of the objects of the invention having 30 been stated, other objects will appear as the description proceeds when taken in connection with the accompanying drawings, in which:—

Figure 1 is a side elevation of my invention; 35 Figure 2 is a top plan view of Figure 1;

Figure 3 is an elevation of the opposite side of my invention from that shown in Figure 1;

Figure 4 is a sectional plan view taken along the line 4—4 in Figure 1;

Figure 5 is a longitudinal sectional view taken along line 5—5 in Figure 2;

Figure 6 is a transverse sectional view taken along line 6—6 in Figure 5;

Figure 7 is a transverse sectional view taken 45 along the line 7—7 in Figure 5;

Figure 8 is a sectional detail view taken along the line 8—8 in Figure 7;

Figure 9 is a sectional detail view taken along the line 9—9 in Figure 3;

Figure 10 is an enlarged detail view showing the means for feeding the tape and applying the same to the top of a package.

Referring more particularly to the drawings the numerals 10 and 11 denote the two side 55 frames or trusses between which my apparatus

is adapted to be mounted. The side frame or truss 10 is comprised of end posts 12 and 13 which are connected together at their upper ends by a suitable top chord member 14, and near their lower ends by a bottom chord member 15. 5 The top and bottom chord members 14 and 15 are tied together by suitable vertically disposed web members 16, 17, 18, 19 and 20.

The end post 12 has projecting therefrom a cantilevered portion 21 which is adapted to support 10 a feeding mechanism which will be presently described.

Likewise, frame member 11 is comprised of end posts 24 and 25 said posts being secured together at their upper ends by a top chord member 26 15 and near their lower ends by a bottom chord member 27. These chord members 26 and 27 have suitable vertically disposed web members 28, 29, 30 and 31 which tie said chord members together. The end post 24 has the cantilevered 20 portion 32, similar in all respects to cantilever portion 21 just described, which is adapted to cooperate with this portion 21 to support the feeding mechanism.

A suitable electric motor 35 is provided for operating my apparatus and this motor has a suitable pulley 36 upon which is mounted a belt 37, said belt 37 being also mounted on a larger pulley 38. The pulley 38 is fixedly mounted on shaft 39 which, in turn, is rotatably mounted in web 30 members 17 and 29.

The other end of shaft 39 has fixedly secured thereon a pinion 40 which is adapted to mesh with idler pinion 40a pivoted as at 40b which idler pinion also meshes with gear 41, said gear 41 being rotatably mounted as at 42 on web member 18. A similar gear 43 meshes with gear 41 and this gear is likewise mounted on a web member 20 as at 44. Gear 43 meshes also with a gear 45 which is fixedly secured on a shaft 46, said shaft 40 46 being rotatably mounted in bottom chord members 15 and 27.

It should be noted that the gears 40a, 41 and 43, just described, serve merely as idler gears to connect the pinion 40 to the gear 45 and the direction 45 of rotation of these gears is denoted by the arrows placed thereon. The shaft 46 has fixedly secured thereon a pulley 49 upon which is adapted to be mounted a suitable conveyor belt 50, said conveyor belt 50 being also mounted upon another pulley 51 which is fixedly secured on shaft 52. Shaft 52 is rotatably mounted in suitable bearings 53 and 54 which are secured to bottom chord members 15 and 27. These bearings are 55

identical in all respects therefore, like reference characters will apply to like parts.

It is seen by observing Figures 1 and 5 that the bottom chord members 15 and 27 have slots 15a and 27a respectively cut in the left-hand ends thereof, through which the shaft 52 is adapted to project. The bearings 53 and 54 each have a slot 56 therein which is penetrated by a stud 57 to hold the bearings in their proper position on members 15 and 27. The right-hand ends of bearings 53 and 54 (see Fig. 4) have laterally projecting portions 58 which are adapted to be contacted by the head of a suitable adjustment screw 59, said screws being threadably mounted in a block 60 which in turn is secured to the bottom chord members 15 and 27. When the conveyor belt 50 becomes slack and an adjustment is desired, it is evident that by loosening the bolts 57, and manipulating the adjustment screws 59 that the pulley 51 may be moved to the left and the proper adjustment duly made.

The other end of shaft 52 has fixedly mounted thereon a pulley 65. Pulley 65 has mounted thereon belt 66 which is also mounted upon a similar pulley 67 which is fixedly secured on shaft 68. The belt 66 is adapted to be contacted by a suitable roller 66a which is rotatably mounted on the arm 66b, said 66b being pivoted in cantilevered portion 32. When the roller 51 on shaft 52 is adjusted by means of the screws 59 and its associated parts the slack in the belt 66 is automatically taken up by means of the roller 66a.

Shaft 68 is rotatably mounted in top chord members 14 and 26 and has fixedly mounted thereon a pulley 69. A second conveyor belt 70 is mounted on pulley 69 which belt is also mounted on a pulley 71 which is fixedly secured on shaft 72, said shaft 72 being rotatably mounted in the ends of cantilevered members 21 and 32. The conveyor belt 70 has secured thereto a plurality of lugs or projections 74 which are adapted to contact the packages to be stamped and to carry them into the machine. These packages will be denoted by the reference character 75 and it will be seen by observing Figures 1 and 3 that a suitable chute 76 is provided through which the packages 75 are adapted to be fed into the conveyor 70.

As the conveyor belt 70 rotates on the pulleys it is seen that these packages will be transferred one by one into a vertically disposed chute 77 which is mounted on top chord members 14 and 26. The chute 77 acts as a supply bin for the belt conveyor 50. Should this chute not be present as the feeding would have to be more accurately timed in order to insure that the feeding to the conveyor belt 50 be uniform, but since the chute 77 is provided and the packages 75 are allowed to be stacked therein by the second conveyor 70 a uniform delivery to belt 70 is not absolutely necessary because enough packages are always disposed within the chute 77 to insure that one package will be ready each time a lug 80 which is disposed on the belt 50 comes upwardly to pull a package out of the chute 77. The lowermost package 75 in the chute 77 is adapted to be contacted by the lug 80 and carried rearwardly in the machine. The chute 77 can be easily removed and a broader or narrower chute installed for packages of varying widths. This is made possible by having pins 77a in chords 14 and 26 which fit into holes in plate 77b supporting chute 77.

Before the label or stamp is applied to the top 75 of the package it is necessary that the surface on

which the label will be attached will be buffed or slightly roughened in order that the moistening device may operate more effectively; therefore, I have provided a buffer or scarifier which consists of a stiff rotary brush 82. This brush is rotatably mounted on a shaft 83 said shaft 83 having its ends rotatably mounted in slidable blocks 84 and 85. The blocks 84 and 85 are slidably mounted in suitable guideways which are secured to the inner side of web members 16 and 28.

In order to adjust the height of the buffer 82 so that the proper roughening or scarifying will take place on the top of the package, an inverted U-shaped member 86 is provided the lower ends of which support shaft 83 and the upper end of said member 86 has screw threadedly mounted therein a shaft 87, said shaft 87 being loosely mounted in a horizontally disposed member 88 which rests on top of top chord members 14 and 26. The upper end of shaft 87 has a suitable hand wheel 89 secured thereon and it is evident that the height of the U-shaped member 86 and the shaft 83 may be adjusted by turning this hand wheel. The buffer 82 is positively driven by means of a pulley 82a which is fixedly mounted on a shaft 83, said pulley 82a having mounted thereon a belt 82b which is also mounted on a pulley 82c fixedly secured on shaft 89. An arm 82d is pivoted in web member 29 and has rotatably mounted on the free end thereof a roller 82e which is adapted to contact the belt 82b. This roller will keep the proper tension in the belt when an adjustment has been made. In order that the packages 75 will be led directly beneath the scarifier 82 suitable guides 90 and 91 are provided for guiding these packages. Guide 90 is supported by an inverted U-shaped member 93 which is slidably mounted on bolts 94 and 95 disposed between top chord members 14 and 26. The upper central portion of inverted U-shaped member 93 is threadably mounted on a rod 96, said rod 96 being rotatably mounted in top chord members 14 and 26 and having a hand wheel 97 thereon. Likewise, guide 91 is supported by a similar inverted U-shaped bracket 98 which also has its upper end slidably mounted on rods 94 and 95 and its upper central portion threadably mounted on shaft 96. Since the threads on shaft 96 are disposed in opposite directions, that is, the threads engaging member 93 are left-hand threads and the threads engaging members 98 are right-hand threads, the turning of hand-wheel 97 will cause the members 93 and 98 to move in opposite directions. When the width of the guides 90 and 91 is desired to be changed, the hand wheel 97 is turned until these members are disposed at the proper position.

After the top of the package 75 has passed beneath the buffer 82 it is next passed beneath a moistening roll 100 in order that the proper moisture may be placed thereon so that a gummed label or stamp will adhere thereto. This moistening roll 100 consists of a grooved pulley having a felt surface 101 thereon which is adapted to have moisture applied thereto by means of a suitable pipe 102 upon which this roll 100 is rotatably mounted. It is seen that the roll 100 has suitable bores 103 leading from the central portion thereof and that the pipe 102 has perforations 104 therein which allow the moisture or liquid to escape from the pipe 102 and onto the covering 101.

The pipe 102 is U-shaped and is pivotally mounted in bearings 105 and 106 which are dis-

posed in the web members 17 and 29. These bearings 105 and 106 are similar in most respects and by referring to Figure 8 it is seen how the pipe 102 is mounted. The bearing 105 consists of a packing nut 107 which is threadably mounted on a short pipe 108 and a suitable packing gland 107a is provided in order that the liquid may not escape as it passes from pipe 108 to pipe 102. By making an arrangement of this type it is seen that the oscillation of the pipe 102 is made possible without allowing any of the liquid to escape therefrom.

The other end of pipe 108 has a vertically disposed pipe 109 connected thereto, (see Fig. 1) which has placed therein a suitable valve 110. The upper end of this pipe 109 is connected to a reservoir 111 which supplies the liquid to the moisture roll 100. As previously stated, the bearing 106 is similar in most respects to the bearing 105, just described, but it is evident that the end of pipe 102 should be plugged as at 102a to prevent the liquid from escaping therefrom.

In order to limit the downward movement of the moistening device 100 an L-shaped member 113 is provided, said member 113 being pivotally mounted as at 114 to bottom chord member 27. It is seen that the upper end of the L-shaped member 113 projects beneath the pipe 102 and by loosening the bolt 114 and pivoting the L-shaped member 113 therearound the elevation of the moistening device 100 can be varied to suit the height of the package. After the moisture has been applied, to the top of the package the label is then placed thereon by a mechanism which will be presently described.

The labels or stamps 115 which are to be applied to the top of the packages 75 are manufactured in suitable rolls and it is seen by referring to Figure 7 that between each label that a row of perforations 116 is provided in order that the label will break at this point after it has been applied to the package. The roll is placed on a suitable stud 117 which is fixedly mounted in top chord member 26. Bolt 117 has a collar 118 slidably mounted thereon, said collar 118 having a slot 119 therein which is penetrated by a pin 120 said pin 120 being secured to the bolt 117. A tension spring 121 is disposed on bolt 117 against the right-hand face of collar 118 (see Fig. 7) and the upper portion of top chord member 26. This spring normally tends to force the collar 118 against the roll of labels and produce a friction on the roll to prevent said roll from unwinding faster than necessary. A nut 122 is threadably secured on the end of bolt 117 and it is evident that by adjusting this nut 122 that the necessary friction on the roll of labels or stamps 115 may be produced.

The roll of labels or stamps 115 is adapted to pass between rubber belts 123 and 134. Belt 123 is mounted on rollers 125 and 126. The roller 125 is fixedly secured on shaft 127 which is rotatably mounted in blocks 128 and 129. The shaft 127 has fixedly secured thereon a pinion 130 which is adapted to mesh with another pinion 131 fixedly secured on shaft 132. The shaft 132 has fixedly secured thereon a roller 133 which is similar in all respects to the roller 125 just described, and upon this roller 133 is a rubber belt 134. Belt 134 is also mounted on a roller 135 which is similar to the roller 126 previously described.

Rollers 126 and 135 have their ends rotatably mounted in stirrup member 140, said stirrup mem-

ber having its upper ends pivotally mounted in suitable projections in sliding blocks 128 and 129. A presser roller 141 is also rotatably mounted in the lower end of stirrup member 140 and is adapted to press the tape of stamps or labels onto the top of the package as it is delivered by the belts 123 and 134.

In order to adjust the height of the stirrup member 140, an L-shaped member 142 is provided and this member is pivoted as at 143 to bottom chord member 27. This L-shaped member 142 is similar to L-shaped member 113 just described and has its upper end projecting horizontally directly beneath the stirrup member 140.

By referring to Figures 3 and 9 it is seen that a pinion 144 is fixedly secured on the end of shaft 132 and on the extreme right-hand end of shaft 132 is rotatably confined an arm 145, the upper end of said arm 145 having a dog pivotally secured thereto and normally having its free end pressed into engagement with the teeth of pinion 144 by any suitable means such as spring 147. The lower end of arm 145 has pivotally secured thereto an adjustable link 150 which is also connected as at 151 to disc 152. The disc 152 is secured on stud 153, said stud shaft 153 having a pinion 154 fixedly secured thereon which is adapted to mesh with a gear 155 which is secured on shaft 46. As disc 152 rotates in a clock-wise manner in Figure 3, due to the rotation of shaft 46, pinions 155 and 154, it is evident that the link 150 will cause the arm 145 to oscillate back and forth. As the disc 152 rotates from the position shown in Figure 3, the pinion 144 will move in a counter-clockwise manner but after the point 151 reaches its extreme right-hand position in Figure 3 and starts its travel to the left, it is evident that the pinion will not be moved but the dog 146 will ratchet over the teeth in the pinion 144 until the point 151 has reached its extreme left-hand position. At this point when the direction of travel of point 151 changes, the dog 146 will again engage the teeth in pinion 145 and cause the pinion to move in a counter-clockwise manner.

It is seen by referring to Figures 3, 5, 9 and 10 that the belts 123 and 134 move to carry the stamps 115 to the package 75 only when the shaft 132 is rotated. The object of providing a mechanism that will cause intermittent movement of the shaft 132 is to provide means for feeding the tape to the package, one label or stamp at a time and after this label has been applied to the package to cause the movement of shaft 134 to cease. The conveyor belt 50 will continue its movement thereby causing the label to break at the perforation 116. When the package 75 first reaches the pressure roller 141 the shaft 132 begins rotation thereby causing the belts 123 and 134 to feed a label from the roll to the top of the package. The shaft 132 continues to rotate until the label has been practically applied to the top of the package as shown in Figure 10 at which time the shaft 132 ceases to rotate to allow the ratchet 146 to ratchet over the top of the teeth in the pinion 144. At the same time the conveyor belt 150 continues its travel causing the label to break at the perforation 116.

In order to provide vertical adjustment for the shafts 127 and 132, an inverted U-shaped member 160 is provided which is similar in all respects to the U-shaped member 86 just described. The upper central portion of the inverted U-shaped member 160 has a bolt 161 threadably secured therein said bolt extending upwardly and being adapted to be rotatably mounted in horizontally

disposed member 162 which is mounted on top of top chord members 14 and 26. A hand wheel 163 is also provided in order that the bolt 161 may be turned to cause the height of inverted U-shaped member 160 to be varied. When the adjustment of the height of shafts 127 and 132 is effected it is of course evident that link 150 will likewise have to be adjusted to correspond to the adjustment made by means of the U-shaped member 160 and its associated parts.

After the label has been applied to the top of package 75 it is then stamped with the name of the owner of the store or the wholesaler who is selling the goods. This requirement is made by the stamp tax laws of several states and in order to cause this stamping to take place after the label has been applied I provide a stamp roll 165 and an ink roll 166 both of which have their ends rotatably mounted in stirrup member 167, said stirrup member being pivotally mounted in web members 29 and 31. It is seen that the ink roll 166 is disposed directly above the stamp roll 165 and is adapted to supply the necessary ink to the stamp pad which is placed on the outside of the stamp roll 165. It is evident that when the package 75 with the label thereon passes beneath the roller 165 that the roller 165 will be caused to rotate and print the indicia or letters on the face of the stamp roll on top of the label. The downward movement of the stirrup member 167 is limited by means of an L-shaped member 168 secured to bottom chord member 27 as at 169. The adjustment of this L-shaped member may be made in the same manner as described for the L-shaped member 113. When the packages have passed beneath the roll 165 they are ready for sale to customers.

It is thus seen that I have provided a means whereby the packages may be roughened and then moistened and a stamp applied thereto and also means for cancelling the stamp. This is done in one continuous operation, thereby saving much

labor which has been necessary heretofore when the stamps were placed thereon and cancelled by hand. It is evident also that the packages do not necessarily have to be of the same shape as shown in the drawings but by changing the chute 77 to one of different dimensions packages which have other dimensions can be fed as well into the apparatus and stamped thereby.

In the drawings and specification there has been set forth a preferred embodiment of the invention, and although specific terms are employed, they are used in a generic and descriptive sense only, and not for purposes of limitation, the scope of the invention being set forth in the appended claim.

I claim:

Apparatus for applying stamps and labels to packages which comprises a framework, an endless conveyor for receiving packages and conveying them through the apparatus, spaced projections on the endless conveyor for engaging packages placed on the conveyor, means disposed on each side of the conveyor for guiding the packages, means for adjusting the position of said guiding means to conform to the size of the packages on the conveyor, vertically adjusting means for roughening the upper side of the packages, means for moistening the upper side of the packages, means for supporting a roll of stamps, means for feeding the stamps in timed relation to the travel of the packages, and means for driving said endless belts intermittently, the stopping of the endless belts after the stamp has been partially affixed to a package while the package is constantly moving serving to tear the stamp from the roll, and means for holding a perforated ribbon roll of stamps, a pair of endless belts for withdrawing the stamps in ribbon form from the roll and feeding them to the packages, an idler roll for pressing the stamps onto the packages.

JAMES A. SANDERS.
